PAGE 2

FIG-3

FIG-6

FIG. 1 is a front perspective view of an umbrella casing in a folded closed position, showing my new design; and FIG. 2 is a rear perspective view of FIG. 1; and

FIG. 3 is a perspective view of FIG. 1 in an open, but zippered position; and

FIG. 4 is a rear perspective view of FIG. 3; and

FIG. 5 is a perspective view of FIG. 3 in a fully opened position; and

FIG. 6 is a rear perspective view of FIG. 5 with flaps spread.

I claim:

The ornamental design for the casing for flat foldable umbrellas, as shown.
